Thomas Leo Ash.

UNITED STATES PATENT OFFICE

2,173,291

AERODYNAMIC ROTOR

Thomas Leo Ash, Los Angeles, Calif.

Application October 10, 1938, Serial No. 234,196

17 Claims. (Cl. 244—18)

My invention relates to aerodynamic rotors and the like for lift and/or propulsion of rotoplanes and other aircraft, and while the invention involves totally new features it is also in the nature of an improvement upon the rotors set forth in Patent No. 2,108,245 issued February 15, 1938, and Patent No. 2,120,168 issued June 7, 1938.

A particular object of this invention is to provide for using only one blade which is dynamically balanced; a single blade having the advantage of moving thru relatively undisturbed air without interference from other blades.

By a reciprocal action on the part of the blades the rotor shown in Patent No. 2,120,168 provides balance all around or offset balance as and where required. An object of this invention is to provide all the advantages thereof but without actually moving the blades with respect to the true center of rotation. Another object of the invention is to provide for using a single blade which provides for placing the preponderance of lift wherever needed at any time.

By employing the feature of decreasing chord, thickness and angle of attack of the blade from the root outwardly, as set forth in Patent No. 2,108,245, those portions of the blade which are near the center of rotation, are highly effective, and the present invention takes advantage of such feature to vary the lift of the blade during each revolution, without subjecting the blade to reciprocal motion.

High cruising speed and increased load are objects of the invention. Heretofore, speed and efficiency have been limited by reason of the wing span required for the characteristic take-off and landing for which rotoplanes are noted. It is an object of this to provide a wing, or wings, which while having suitable span for customary take-off and landing, can be positively retracted to a shorter span in keeping with some of the objects of the invention.

Specifically, it is an object of this invention to provide a blade which can be extended to suit landing and take-off requirements but which in cruising position is quite rigid and which is so controlled thru each and every part of each revolution that its centrifugal force is not employed to hold it in proper position. In fact I provide, by this invention a blade which in cruising position is of itself decidedly rigid independently of centrifugal force but which is provided with means for suitably snubbing forces which would otherwise be damaging to a structurally rigid blade.

Other objects and advantages of my invention

will appear hereinafter and will be better understood by reason of the order in which they appear.

I have illustrated by the accompanying drawing, one practical embodiment. In the drawing:

Figure 1 is a view mainly in vertical section of such an embodiment.

Figure 2 is a smaller scale plan view of said embodiment; this view showing the blade in position for banking to the left, for example.

Figure 3 is a small scale elevation showing the blade in the position shown by Figure 2.

Figure 4 is a view in elevation similar to Figure 3 but showing the blade fully extended.

In the embodiment illustrated, and in common with Patent No. 2,120,168, the wing is made up of a plurality of telescoping sections such as 7, 8, 9, 10 and 11 respectively and each is provided with an attached cable such as 12; the wing including the reel 14 having graduated winding surfaces such as 15; one such surface for each cable. The reel includes an integral pinion 16 and is mounted to rotate on a fixed shaft 17.

To rotate the reel positively, as required, any suitable mechanism, as taught by the prior art may be employed and by way of example I have here shown a rack 18 engaging the pinion 16. This rack is hydraulically driven; there being an integral plunger 19 at one end of the rack reciprocal in a hydraulic cylinder 20. The cables are so wound on the reel that centrifugal force acting to pull the wing sections outwardly will rotate the reel so that the pinion acts on the rack to move the piston or plunger 19 inwardly of its cylinder 20. This will act to displace oil or the like, contained in the cylinder, outwardly thru the port 21. Means for controlling the escape of fluid from a hydraulic cylinder, and for forcing fluid into such cylinders, are well understood and are not further described or illustrated herein. It will be understood however, that the hydraulically operated reel here shown will provide for controlling the rate at which the wing can expand under centrifugal force, and will provide for positively contracting the wing as required and for holding same in any retracted position.

A salient feature of the invention resides in housing the reel 14, the shaft 17, the pinion 16, and the hydraulic device, all compactly within the section 7 of the wing. This root section 7, for this reason and for purposes of balance, is extended as at 7a in diametric opposition to the main extent of the wing, and altho in this embodiment the rotor may be described as single-

bladed, this extent $7a$ does do some lifting, as will appear hereinafter.

The true center of rotation of the wing or blade is located inwardly from extension $7a$ and at the center of rotation and on the under side, the blade, at section 7 , is provided with a pivot shaft 22 which is mounted within a boss 23 forming an integral part of the wing section 7 . This provides for the wing pivoting on an axis right-angular to the longitudinal axis of the wing. While such pivot has been provided in prior aircraft to provide for automatic "coning" or for positive "coning" thru the aid of mechanical devices, I provide this pivot as part of a "snubbing" device which prevents undue strains on the root section of the wing.

Another part of the snubbing device is provided in the form of a counter-weight W carried at the outer end of a cable 25 . This cable is wound upon a special winding surface $25a$, also provided by the reel 14 , and this winding surface provides that for any position to which the wing sections are extended, the cable 25 will have corresponding unreeled length and thru centrifugal force will provide for dynamically balancing the single wing. This cable extends out from extension $7a$ thru a tube 26 ; which tube is downwardly directed to hold the cable 25 and weight W at a plane of rotation lower than that of the wing. This not only prevents the cable from moving in the same plane, and thru the same air, thru which the wing moves, but it causes the weight W to act at all times during rotation to keep the wing in a nearly level or horizontal position. Therefore, no stops are needed for the pivot 22 . Thus the weight W not only acts as a balance for the single wing, but it also provides the aforesaid snubbing device to protect the otherwise quite rigid wing from sudden stresses which might produce a twist or shear at the root section 7 . Also the combination of the pivot 22 and the weight W provides an ideal means for suspending aircraft from a rotary wing or lifting system.

45 The numeral 27 indicates a part, either the roof or the pylon of an aircraft body (not shown further) which is supported by the wing, and such part is shown as providing the usual thrust bearing 28 , thru which extends the rotor shaft 29 . This shaft, below the member 27 , is provided with a set of bevel gears, indicated at 30 , which connect the shaft 29 with a power shaft 31 ; it being understood that in rotoplanes the rotor is started by power. I further propose to use this shaft 31 and gears 30 , at times, to connect the rotor of such a craft (with the usual propeller) to apply any excess turning effort of the rotor to use in providing a long and otherwise powerless glide.

60 The rotor shaft is provided at the upper end with a bracket 32 in which the pivot 22 is carried so that while the wing may pivot it is connected to the rotor shaft for positive rotation therewith. Altho the wing being described provides for meeting various loads by being extended as required and does not depend, as do prior rotors, for changing angle of attack, I have shown the pivot shaft 22 as having right-angular extensions or arms 34 mounted to pivot in bracket 32 so that 65 the angle of attack of the wing may be changed if desired. For instance, to show the efficiency and stability of craft to which this invention is applied, inverted flying and other stunts may be resorted to. This would require changing from 70 positive angle of attack to a negative angle so

that when the craft is inverted the angle of attack will be effective positively. Also I show this type of pivot to remind those skilled in the art that the weight W may be positioned so that it will act to control angle of attack. The weight W may have any suitable cross section and this section may be such as to give either positive or negative lift, but of course minimum drag is important. In Figures 2, 3, and 4 respectively, it is shown only diagrammatically while in Figure 1 it is shown elongated and hinged centrally as at 35 so that it will not project unduly when in retracted position.

In Figure 4 the blade is shown fully extended and it is a feature of the invention that when the blade is so extended it will cone slightly to give stability during landing, takeoff and slow speed, while in Figure 3 the blade is shown about one-half retracted.

This partially retracted position provides inherent structural rigidity on the part of the blade and while the shortened wing provides the required lift at cruising speed it offers much less drag than were the wing required to be always extended to the span required for landing and take-off. In the embodiment illustrated the action of weight W at the regular cruising speed is such as to permit little or no coning on the part of the relatively rigid short blade, altho this same weight and the pivot do allow for coning in an emergency where a rigid non-coning blade might be damaged.

Pivotal mounting of the blade in combination with the action of weight W is particularly advantageous in take-off where the blade is first revolved by power and then suddenly expanded to provide a sudden vertical take-off, for under those conditions this blade, which of itself is quite rigid, will be suddenly subjected to reactions far greater than the weight of the aircraft.

It will be apparent now that I have provided a blade which is structurally rigid and which does not depend upon its centrifugal force to keep it suitably rigid, but which blade is so mounted and so controlled by the weight W that it will pivot under extreme load or sudden changes of air density. Thus the advantages of a rigid blade are enjoyed while the previous disadvantages are overcome. As compared with prior aircraft of the type to which this invention more particularly relates, the reduced drag of the blade and the higher speeds made possible by this invention, result in ample lift from a single relatively short and rigid blade. At the higher speeds contemplated by this invention little or no coning action is required.

While this single blade is dynamically balanced it is also aerodynamically balanced thruout all parts of each revolution. While aerodynamic balance has heretofore been attained by other means, the present invention provides such balance by means which has no adverse effect upon dynamic balance.

Said means includes a "full-floating" hub 39 which encloses those parts of the wing in the vicinity of the center of rotation and this hub is movable to, and adapted to be held in, any eccentric position, such as the position in which it is shown in Figures 2, 3 and 4. In Figure 1 it is shown fully concentric with the center of rotation.

The means for shifting the hub comprises an arm 40 which passes up thru the hollow of the hollow rotor shaft, then thru the pivots, then thru the wing section 7 where it is supported rev-

olubly by opposed thrust bearings 41 and 42, and thence into the hollow 39a of the hub 39. Aper-tures 43, provided in the hub, have enough clearance, where the blades project as at 43a, to permit of the blade being tilted without the hub being tilted. Within the hollow of the hub, and above the wing, there is provided a hydraulic cylinder 44, fixed to the hub as at 44a. This cylinder is horizontal as is the arm 40, which arm 10 turns at 40a and after passing into the cylinder, terminates in a plunger 45. The arm is hollow thruout and at the lower end is enlarged to provide a second hydraulic cylinder 46 which, thru the hollow arm 40 communicates with the bore 15 of the cylinder 44.

A bracket 48 is connected rigidly to the cylinder 46 and to this bracket is pivoted, as at 49, a lever 50. This lever is in reality the "stick" by which the craft is controlled. Within the cylinder 46 is a plunger 51 connected to the lever 50 by a link 52. Thus when the outer end 50a of the lever is depressed, fluid contained in cylinder 46 will be displaced thru the hollow of arm 40 into cylinder 46.

25 The hub, or at least a portion thereof, is non-rotative so that the arm 40 may be pointed in any direction and held there. Accordingly, the lower part 39b of the hub is provided with an annular bearing 54 so that it may turn within the 30 hub and rotate with the wing.

While the operation of some parts has been described herein, the operation of the rotor as a whole will be understood from the following:

With all parts in the idle position indicated by 35 Figure 1 take-off may be accomplished by power rotation of the rotor shaft. As the rotative speed increases the wing sections tend to fly outward, restrained by fluid in the cylinder. When suitable rotative speed is reached the sections are 40 allowed to move out. If this is done suddenly and the wing expanded to full span the lift becomes considerably greater than the weight of the craft to which it is attached and a rapid rise or take-off will result. As soon as the aircraft is under 45 way the wing may be contracted to a span just sufficient to sustain the craft while setting up the minimum of drag. Since the root section 7, and the extension 7a where it projects from the hub, has as much lift per unit of length as do other sections, the wing is effective right down to the hub.

It will be found that for level flying under normal conditions a slightly eccentric position of the hub will provide aerodynamic balance so that the wing will show equal lift in all parts of the disc area and there will be little or no tendency for the wing to "flap". In fact this rigid wing is not designed to flap and will not even tilt on its pivot, or cone, except under a temporary load greater than that found in normal flight at cruising speed. Whenever the blade is expanded or contracted the weight moves in or out accordingly, since its cable is wound on the same reel as that upon which the blade-section cables are wound. Thus dynamic balance is always provided.

To bank the aircraft to make a turn, or to nose it up in a climb, or down in a dive, the stick is turned to point in the desired direction. Thus 70 in Figure 1 it is shown pointing to the left, which means that cylinder 44 is pointing in the same direction. Now, by depressing the stick slightly the cylinder 46 and its plunger act as a pump to move fluid in to cylinder 44 to thus move the hub in that direction away from the center of rotation

of the rotor and into the position in which it is shown in Figure 2.

The concentric lines 53 in Figure 2 show the path of the corresponding end of each of the blade sections. It will be seen from this that section 7 while passing thru the right-hand side of the disc area is fully effective in producing lift while section or extension 7a is also effective in producing lift when passing thru the right-hand part of the disc area. However, both of these 10 are moved into the hub and are quite ineffective when passing thru the left-hand part of the disc area. Accordingly the wing has much greater lift on the right-hand portion and this will cause the craft to bank and turn to the left; just as is 15 indicated by the stick. A right-hand turn, a climb, or a dive may be brought about in the same manner by swinging the stick around to point in the desired direction while depressing the outer end of the stick. Raising the end of the 20 stick to bring it back to the level position in which it is shown in Figure 1, will draw fluid out of cylinder 44 and create a suction which will return the hub to any less eccentric or to fully concentric position.

25

Certain features of the invention, such as the shifting hub and the positively contracted wing, may be employed with more than one blade, as may also the combination of the pivot and snubbing device. Also the pivoted blade, either in a 30 single-blade or multi-bladed wing may be used with other means for snubbing.

This disclosure will suggest to those skilled in the art many other modifications, such as employing some of the features of this invention in 35 a flexible wing, altho I hold that I am first in the art to make it really practicable to employ a blade which is decidedly rigid; which does not tend to flap because it is aerodynamically balanced all around the disc area; and which blade 40 has increasing rigidity with increase of speed by reason of the fact that it can be retracted to such span for each speed and load combination as to give just the right lift with minimized drag. Also 45 in quick vertical take-off rigidity of the wing or blade is not a detriment since snubbed coning can take place. Also this invention results in a further advantage from using blade sections of increasing chord, thickness and angle of attack inwardly; this providing uniform lift from root 50 to tip and evenly distributing the load so that rigidity becomes an advantage rather than a disadvantage. A further advantage of having the root section equally as effective as the other sections is that excess lift may be thrown on any 55 determined part of the disc area by merely shifting a light-weight hub. I am aware that even the very light-weight revolving part of the hub may tend to vibrate very slightly but it will be seen that the hydraulic shifting means for same provides a non-positive connection between the hub and the rest of the assembly so that dynamic balance as a whole is not altered. It will also be understood that the invention applies to a propeller as well as to a lifting rotor, and may also 60 be applied to fans and other aerodynamic rotors.

I claim:

1. In a rotor of the class described, an airfoil blade comprising a plurality of telescopically associated airfoil sections of increasing chord, thickness and angle of incidence respectively inwardly of the blade whereby the blade has substantially constant lift per unit of span from the tip to approximately the center of rotation, a movable hub normally co-axial to the center of rotation 75

of said blade and enclosing the blade for an appreciable distance outwardly from its center of rotation, and means for eccentrically shifting said hub.

2. The rotor as in claim one and including means operable during rotation of said blade and independently of said hub-shifting means for contracting said blade against centrifugal force.

3. The rotor as in claim one and in which said hub includes a plate superposed immediately over said blade, and said shifting means includes an extension element for said plate radial to the center thereof and means for moving the element radially about the center of rotation of said blade.

4. The rotor as in claim one and further including, a winding reel carried in the innermost section of said blade and provided with a plurality of graduated winding surfaces, cables, one for and attached to each wing section and each wound on a corresponding winding surface.

5. The rotor as in claim one and further including a stub-end to the innermost section of said blade projecting radially from the center of rotation of said blade in diametric opposition to other parts of the blade, a centrifugal weight and a cable connecting said weight to said stub-end.

6. The rotor as in claim one and in which said last named means comprises; means for turning said hub about the center of rotation of said blade, and means for moving the hub radially outward with respect to said center of rotation.

7. In a rotary lifting system for aircraft, a central rotary shaft, a single airfoil blade carried by said shaft extending approximately radially thereof, a cable extending radially with respect to said shaft from the inner end of said blade in diametric opposition thereto, and a relatively small area weight carried at the outer end of said cable to provide dynamic balance.

10 8. The system as in claim seven and including means for contracting said wing and for winding in said cable co-ordinately to provide maintained dynamic balance.

9. The system as in claim seven and in which said cable and said blade are disposed to move in planes of differing elevations.

10 10. The rotary lifting system as in claim seven and in which said blade is structurally rigid and pivoted to said shaft so as to be free to cone; said cable connected to said blade so that the centrifugal force of the weight tends to resist coning of the blade.

11. The system as in claim seven in which said blade comprises a plurality of blade sections telescopically associated so as to provide rigidity independently of centrifugal force.

12. In a rotary lifting system for aircraft, a central shaft, a blade section projecting radially

from said shaft, a second blade section telescopically housed in said first section, and a winding reel housed in the inner end of said first section, a cable attached at one end to said second section and having its other end coiled around said winding reel, a motor housed in said first section for rotating said winding reel, a second cable wound on said reel and extending thru the first section outwardly in diametric opposition to the sections, and a weight connected at the outer end 5 of said cable acting to dynamically balance said sections.

13. The rotary lifting system as in claim twelve and including a pivot connecting said inner section with said shaft to allow said sections to cone; 15 said weight and corresponding cable acting under centrifugal force to resist such coning.

14. The rotary lifting system as in claim twelve and including an eccentrically shiftable hub enclosing the inner end of said first section normally 20 co-axial with said shaft, and means for shifting said hub eccentrically of the center of rotation of said sections.

15. The rotary lifting system as in claim twelve and further including a freely floating hub enclosing the inner end of said first section, a second shaft within the first shaft supporting said hub and adapted to be turned, a piston projecting horizontally radially from said second shaft, a cylinder carried by said hub and containing said 30 piston, means for turning said second shaft and means for injecting fluid into said cylinder.

16. In an aerodynamic rotor, a shaft, a single blade projecting from and driven by said shaft, a hub normally enclosing the corresponding portions of said blade, and means for moving said hub axially of said blade and for then constraining said hub to rotate with said blade around a point eccentric to the shaft.

17. In a rotary lifting system for aircraft, a hub, 40 a single blade projecting radially from said hub, a dynamic balance weight for said blade, a cable extending from said hub in diametric opposition to said blade and connected at its outer end to said weight, said system including means operable once during each revolution of said blade to retract said blade relatively inwardly of said hub during a predetermined part of each revolution and to allow said blade to move relatively outwardly of said hub during other portions of the 50 revolution; said means acting to move said cable relatively outwardly of said hub when said blade is being moved inwardly relatively thereof, and to move said cable relatively inwardly of said hub when said blade is moving relatively outwardly 55 of said hub.

THOMAS LEO ASH.
